UNITED STATES PATENT OFFICE.

CHARLES R. DENNISON, OF YOUNGSTOWN, OHIO, ASSIGNOR OF ONE-THIRD TO J. B. CHAMBERS AND ONE-THIRD TO W. V. BURNETT, BOTH OF YOUNGSTOWN, OHIO.

PLACER-MINING MACHINE.

1,064,296.

Specification of Letters Patent.

Patented June 10, 1913.

Application filed January 11, 1912. Serial No. 670,661.

To all whom it may concern:

Be it known that I, CHARLES R. DENNISON, citizen of the United States, residing at Youngstown, in the county of Mahoning and State of Ohio, have invented certain new and useful Improvements in Placer-Mining Machines, of which the following is a specification.

This invention relates to the subject of 10 placer mining, and particularly to an improved construction of placer-mining machine embodying simple and practical means for effectually carrying out the process of recovering gold from placer deposits by simple 15 washing, in combination with accessories that provide for separating and carrying away the coarser material.

To this end the invention contemplates a 20 construction of placer-mining machine embodying improved means for riffling the gold-bearing material and means for utilizing a body and column of water in such manner that it may be used repeatedly through the riffling sluice-way, thus effecting 25 great economy in water and also avoiding the carrying away of much fine gold which is the great desideratum of placer-mining machines wherein the water is used at once and flows off to the waste.

30 Another object of the present invention is to provide a novel construction wherein the sluice-way is of open formation and hence readily accessible at all points thereof for the recovery of the gold collected by 35 the riffles, and also wherein the sluice-way and a circulating flume for water are so related to each other, and to a water-tank or reservoir, that the tailings or waste are separated from the water at the bottom of the 40 sluice-way, and the water alone is reelevated to a point for delivery again into the sluice-way at the receiving end of the latter.

With these and other objects in view, which will be readily apparent to those 45 skilled in the art as the nature of the invention is more fully understood, the same consists in the novel construction, combination, and arrangement of parts hereinafter more fully described, illustrated and claimed.

50 While susceptible of structural modification, a preferred and practical embodiment of the invention is shown in the drawings, in which—

Figure 1 is an elevation of a placer-min-

ing machine embodying the improvements 55 contemplated by said invention. Fig. 2 is an enlarged sectional view of that part of the machine which includes the sluice-way, the water-tank, the circulating flume, and the adjacent accessories. Fig. 3 is a top 60 plan view of the sluice-way, the view also showing the relative positions of the water-tank, the circulating flume, and the water conduits for feeding the water from the latter to the receiving end of the sluice-way. 65 Fig. 4 is an end elevation of the machine showing the relative relation of various parts within the supporting framework.

Like references designate corresponding parts in the several figures of the drawing. 70

The various working parts of the machine, including the stationary and movable elements, are carried by a suitable framework designated in its entirety by the reference numeral 1, and at a convenient location 75 therein is arranged a riffling sluice-way of novel construction. This riffling sluice-way is designated by the numeral 2, and essentially comprises a boxing or casing of suitable capacity and dimensions, and having 80 therein upper and lower reversely inclined sluice-sections 3 and 4, respectively. The separate sluice-sections 3 and 4 are of duplicate formation, that is to say, each of the same is constructed with a downwardly inclining bottom wall 5 upon the upper side of which is arranged a continuous series of transverse riffles 6, of suitable design, and which are intended to perform the usual function of arresting and detaining the gold 85 which separates from the water and coarser material circulating downwardly through the sluice-way. The sluice-way is also of open formation throughout in order that both sections thereof may be readily accessible 90 at all points for the recovery of the gold collected by the riffles, and in order to secure the continuous operation hereinafter more particularly referred to, it will be observed that the upper and lower sluice-sections 3 100 and 4 are reversely inclined to each other and lie in different vertical parallel planes. To provide the necessary communication between the two sections of the sluice-way, the latter is provided with a return channel 105 or bend 7 constructed within the sluice-way casing or boxing transversely thereof at the lower end of the upper sluice section,

and at the upper end of the lower sluice-section, and in communication with both sections.

Immediately adjacent to, and in communication with, the lower end of the lower sluice-section 4, the casing or boxing containing the sluice-way is constructed with a water-tank or reservoir 8, within which is arranged a vertical screen-wall 9 that divides the tank into two compartments, one of which compartments, 10, performs the function of a tailings or waste bin, and the other of which compartments, 11, constitutes a water reservoir proper for the lower end of a circulating flume 12, that is arranged vertically and is built on to the sluice-way at one end thereof. The lower end of this circulating flume 12 is in open communication with the reservoir proper or water-chamber 11, while the upper end of the said flume opens laterally into a plurality of curved or elbow water conduits 13 that deliver water from the flume on to the receiving or upper end of the upper sluice section 3. The water from the chamber 11 is positively forced or lifted upwardly through the flume 12 by means of lifting propellers, turbines, or equivalent elements 14. A suitable number of these elements 14 are employed and the same rotate horizontally within the flume and are carried by a vertical propeller shaft 15 extending through the flume and projecting to the exterior thereof, where the same has a suitable driving connection, 16, as may be plainly seen from Fig. 2 of the drawings.

The sluice-way, at the upper end of the upper sluice-section, receives the gold-bearing material from a feeding chute 17, that is arranged beneath and suspended from a shaking separating screen, 18. The chute 17 is set at a sufficient angle to the body of the screen 18 in order to insure the free delivery of the gold-bearing screenings into the receiving end of the sluice-way, and the said screen body is also set at an angle and is adjustably suspended from swinging hangers 19, loosely hung from the top of the framework, as at 20. The said shaking separating screen 18 performs the functions of a screen of this type, namely, to effect a separation of coarser and finer materials from each other, and for that purpose has fitted within the body thereof one or more screen bottoms 21 of suitable mesh, according to the number and fineness of separations desired, and in order to give the necessary shaking or vibrating movement to the said screen the latter has connected therewith a suitable operating device, which may consist of a pitman 22, having a connection as at 23 with the screen body, and a crank or equivalent connection 24 with one of the operating shafts 25 of the machine.

65 The coarse and unscreened gold-bearing

material is received into the upper end of the separator 18 from the buckets of an endless bucket, or equivalent, elevator 26, whose opposite portions are arranged over the upper and lower belt-drums 27 and 28, respectively, and one of which drums is driven by any suitable means, such as the belting arrangement shown in Fig. 1 of the drawings. The buckets of the conveyer 26 collect the raw material from a supply hopper 29 of suitable construction which is built onto the framework at one end of the base thereof. As the buckets of the elevator 26 pass over the upper drum 27 they discharge into the separator 18, and a deflecting shield 30 arranged at this discharging point, and above the separator, prevents the scattering of the material. The coarse material that does not fall to the chute 17 is delivered from the separator 18 on to an endless belt or equivalent discharging conveyer 31 arranged within the upper part of the framework, and leading to a dump or other point of deposit for the tailings or waste. Likewise the tailings or waste material that fall into the tailings or waste bin 10 are automatically collected and elevated from said bin by means of a bucket-elevator 32, having perforated buckets that will allow the water to drain therefrom and which provide for carrying off the material that has been deprived of its gold and discharging the same into a discharge hopper 33 arranged at the top of the framework and having a laterally inclining outlet spout 34 that extends over the discharging conveyer 31, as may be best seen in Fig. 4 of the drawings. The said elevator 32 is arranged to pass over the upper and lower elevator drums 35 and 36, respectively, and one of which drums may be conveniently driven by means of the belt and pulley arrangement shown in Fig. 1 of the drawings, and at this point it may be observed that the central drive shaft 37 furnishes the point of drive from which, by means of any suitable arrangement of belts and pulleys, mechanically and positively operates all of the conveyers, the separator 18, and the lifting propellers in the flume.

From the foregoing it is believed that the construction and operation of the machine will be readily apparent, and it will be observed that this operation involves the repeated using of the same water, thus insuring a maximum collection of gold.

I claim:

1. In a mining machine of the class described, the combination of a water tank, concentrating means including a pair of reversely inclined sluiceways which are arranged above and mounted upon the tank, perforate walls providing a tailings bin within the tank, said tailings bin being in communication with the discharge end of the lower sluiceway section, an upright cir-

culating flume mounted upon the tank, the lower end of the circulating flume communicating with the tank upon the exterior of the tailings bin while the upper end of the 5 circulating flume is adapted to discharge into the upper end of the upper inclined sluiceway, mechanical lifting and circulating means within the upright flume, and mechanical means for removing the tailings 10 from the tailings bin.

2. A machine of the class described comprising a water tank provided at an intermediate point with a tailings bin, and with perforate walls for such bin, concentrating 15 means supported on the tank and discharging into the tailings bin, an upright circulating flume also carried by the tank and disposed outside of the bin and at one side of one of the perforate walls of the bin, the 20 lower end of said flume being in open communication with the reservoir within the tank, and the upper end of the flume having a discharge connection with the upper receiving end of the concentrating means, 25 lifting and circulating devices within the

flume, and discharging means operating within the said tailings bin of the tank.

3. In a mining machine of the class described, the combination of a water tank provided with a tailings bin, an inclined 30 sluiceway mounted within the tank and having the lower end thereof constructed to discharge into the tailings bin, an upright circulating flume having the lower end thereof in connection with the water tank upon 35 the exterior of the tailings bin, a lateral discharge spout at the upper end of the circulating flume, mechanical lifting means within the circulating flume, a curved water conduit at the upper end of the inclined 40 sluiceway for receiving the water from the spout of the circulating flume, and mechanical means for removing the tailings from the tailings bin.

In testimony whereof I hereunto affix my 45 signature in the presence of two witnesses.

CHARLES R. DENNISON.
